UNITED STATES PATENT OFFICE.

MANUEL BOUZO, OF HABANA, CUBA.

PLOW.

Application filed May 21, 1923. Serial No. 640,480.

This invention relates to improvements in plows.

One of the objects of this invention is to improve the structure of plows, to strengthen the same and enable them to be readily assembled and disassembled.

Another object of the invention is to provide means between the ground working pieces and the seat bar of the plow to regulate at will the depth at which the share is to operate in the ground.

Another object of the invention is to provide an improved construction of the share and its supporting means to render them more durable.

The invention is described with reference to the figures of the annexed drawing, in which:

Fig. 1 is a side elevation of a moulding plow provided with the improvements forming the subject matter of this invention.

Fig. 2 is a plan of the same.

Fig. 3 is a longitudinal vertical section on line 3—3 of Fig. 2.

Fig. 4 is a perspective detail view of the mould-board.

Fig. 5 is a perspective detail of the share and its support.

Fig. 6 is a side elevation of a modified form of plow, arranged for use as a trench plow.

Fig. 7 is a plan of said modified form.

Fig. 8 is a partial longitudinal vertical section on line 8—8 of Fig. 7.

Fig. 9 is a horizontal section on line 9—9 of Fig. 6.

Figs. 10, 11 and 12 are perspective views, respectively, of the share and its support, of the mould-board and of the connecting piece.

In the drawing, 1 indicates the beam of the plow which is secured by bolts 2 and nuts 2' in the fork at the front end of the seat bar 3 of the plow. Said bar is metallic and of curved form, having a widened central portion 4 provided with a longitudinal slot 4' for the object hereinafter explained. The seat bar 3 is pivotally connected by a horizontal pin 5 secured in a slot 7 formed

in the heel 8 of the plow by a pin 5 and split pin 6. Said heel is curved rearwardly at its upper end and terminates in lateral wings 9 which are also rearwardly and upwardly inclined, and to which are secured the handle bars 11 of the plow by bolts 10.

Hand grips 11' are secured to the bars 11, and the latter are connected together by a cross bar 12. Shank of heel 8 is inserted in a slot of bed 13 which is made of forged iron and is integrally connected at its fore end 60 to the share which is made of the same class of material forming the bed 13. Said share is made of flat iron comprising an upper portion 14, a front upwardly directed abutment 14' and a side portion downwardly 65 inclined 14'' which forms an arcuate angle with the wedge shaped end of the bed 13. The part 14 is designed to receive the lower fore portion of the mould-board 15 which projects laterally and is integral with a 70 curved upwardly directed bar 16. Mould-board 15 is fixed to the part 14 by bolts 17 which pass through corresponding holes 18 and 19 in mould-board 15 and part 14 respectively and are secured by nuts 20. The 75 bar 16 has at a distance above the mould-board 15 a lateral abutment 21 which bears on the upper end of a curved link 22 connecting the bar 16 with the bed 13 and which is secured by pins 23 and 24 and nuts 80 25 and 26. The mould-board is also connected to bed 13 by a brace 27 having terminal eyes 27', one of which is fixed to the mould-board 15 by a screw 28 passing through a hole 29 in the mould-board and secured by a corresponding nut. The inner eye 27' of brace 27 is connected to a projection 30 of the seat bar 13 by means of a pin 31 and nuts 32.

From the upper end of bar 16 projects a 90 threaded stem 33 which passes loosely through slot 4' of seat bar 4 and is fixed with respect to the same by means of an upper wing nut 34, a washer 35 and a lower wing nut 36.

At the front end of the beam 1 is arranged a clevis 37 provided with an eye 38 and connected to the sides of the beam by means of bolts 39. A small plate 40 is fixed on the upper face of beam 1 by bolts 41 and has a link 42 connected to an eye 41' of said plate 40. A vertical bar 44 is secured to the beam by a clamp 43 and carries the guiding wheel 45.

To regulate the depth at which the point 105 14'' of the share is operated in the ground, nuts 34 and 36 are loosened, the threaded stem 33 is adjusted in the slot 4' of seat bar 3 to the desired position, and the said nuts are then tightened. As the seat bar 3 is 110

fulcrumed at 5 to heel 13, the angle of heel 8 and bed 13 is thus changed with respect to seat bar 3.

In Figs. 6, 7, 8, 9, 10, 11 and 12 is shown a modified form of plow which is particularly designed for use as a trench plow. In this form of plow the bed 13 has two lateral extensions in the form of supporting clamps 46 and 47 designed to receive the shanks or 10 reduced portions in which respectively terminate at its lower end the heel 8 and the vertical knife 48, the latter replacing the bar 16 of the form previously described. Said knife 48 has the threaded stem 33. In 15 this form, the share is not provided with the part 14 and the mould-board 15 is independent and has an inverted surface at the rear part with respect to the front part for inverting the ground raised by the share. Share 15 is secured to the mould-board 14" 20 by means of a union plate 48' which has two rows of holes 49 and 50 and is applied under the adjacent portions of the mould-board 15 and of the share 14", and is fixed 25 by rivets 50 which pass through corresponding holes 51 and 52 respectively formed in the mould-board 15 and the share 14". The mould-board 15 is reinforced by braces 53 and 54 similar to brace 27 previously described and by means of which the mould-board is connected to the bed 13 by means of countersink screws 55 and 56 which pass through side holes 57 and 58 in the supporting clamps 46 and 47 and through holes 30 formed in the shanks of the heel 8 and of the knife 48 and which are secured by the 35 nuts 59 and 60 respectively.

This modified form of plow is adjustable according to the depth it is desired to plow the ground, in the same manner as previously 40 explained for the moulding plow.

It should be understood that the details of construction of the parts of this plow can be slightly varied without altering the essential character of the invention, which is 45 as pointed out in the appended claims.

What I claim is:

1. A plow comprising a beam having a downwardly-curved standard portion, a bed member, a share integrally formed thereon, 50 a connection member adjustably connected to the beam and rigidly connected to the bed member, handles, and an element to which said handles are rigidly attached, said element being pivotally connected to said 55 downwardly curved standard portion and rigidly connected to said bed member.

2. A plow comprising a beam having a downwardly-curved standard portion, a bed member having a socket at the middle portion 60 and another socket at the rear portion, a share integrally formed on the fore portion of the bed member, a connection member adjustably connected to the beam and rigidly connected to the bed member in the 65 middle socket thereof, handles and an element to which said handles are rigidly attached, said element being pivotally connected to said downwardly curved standard portion and rigidly connected to the bed 70 member in the rear socket thereof.

In witness whereof I affix my signature.

MANUEL BOUZO.
